UNITED STATES PATENT OFFICE.

JOSEPH TURCEK, OF CLEVELAND, OHIO.

DISPLAY-STAND.

1,258,276.

Specification of Letters Patent.

Patented Mar. 5, 1918.

Application filed March 21, 1917. Serial No. 156,376.

To all whom it may concern:

Be it known that I, JOSEPH TURCEK, a citizen of the United States, residing at Cleveland, in the county of Cuyahoga and State of Ohio, have invented certain new and useful Improvements in Display-Stands, of which the following is a specification.

This invention relates to certain new and useful improvements in display stands.

The primary object of the invention is the provision of a display device for any desirable articles, the same being provided with revoluble means for attracting the attention of the public as well as for the purpose of rendering the articles viewable from all sides thereof.

A further object of the device is to provide a revolving display case capable of exhibiting articles contained therein and arranged with a top compartment serviceable for such purposes as the holding of a phonograph for making suitable announcements, a propelling motor for the device being arranged at the base thereof.

With these general objects in view and others that will appear as the nature of the invention is better understood, the same consists in the novel construction, combination and arrangement of parts hereinafter fully described, illustrated in the accompanying drawings and pointed out in the appended claims.

In the drawing forming a part of this application and in which like numerals refer to corresponding parts throughout the several views,

Figure 1 is a front elevation of the device with a portion of one section thereof removed.

Figs. 2 and 3 are horizontal transverse sectional views taken respectively upon lines II—II and III—III of Fig. 1.

Fig. 4 is a horizontal sectional view taken adjacent the lower portion of the device.

Fig. 5 is an enlarged detail horizontal sectional view through one of the detachable connections, and,

Figs. 6 and 7 illustrate in perspective the details of one of the locking connections for the separable sections of the device.

Referring more in detail to the drawing, the present display case 10 is of a general cylindrical form being revolubly mounted in an upright position upon a base 11 and

adapted to be revolved thereon by a motor 12.

The case 10 is formed of two oppositely positioned identical sections 13 and 14 semi-circular in cross section each of the same having a glass wall 15, while a partition 16 is carried by the section 14 being of circular formation and providing a chamber in the upper part of the case 10.

It will be understood that the circular top 17 of the case is formed of two semi-circular portions one of which is carried by the top of each of the sections 13 and 14. A glass panel 18 is provided in each side of the upper portion of the case having a packing strip 19 of metal or wood adapted for receiving advertising matter between the said glass panel and packing, readily viewable exteriorly.

The base 11 comprises perpendicular positioned leg members 20 having an upright shaft 21 centrally journaled therein and secured axially of the case 10 with the top of the shaft fixed to the lower face of the partition 16 and whereby the case is revolvably positioned upon the base 11. Upright posts 22 are carried by the legs 20 having rollers 23 upon their upper ends for revolvably supporting a circular track 24 upon which the case 10 is secured, the track 24 being attached thereto by means of perpendicular strips 25 permanently secured to the section 13. Braces 26 connect the posts 22 together.

Radially projecting arms 27 are carried by the shaft 21 for supporting articles to be displayed such as neck ties and other wearing apparel, the same being readily viewable through the glass sides 15 of the case during the revolving thereof under the influence of the motor 12. Each of the case sections 13 and 14 is provided with a tray 28 of semi-circular form at the bottom thereof mounted upon the strips 25, the said trays being readily lifted when desired for obtaining access through the bottom of the case, the trays having central recesses 29 for accommodating the shaft 21 therein. The side moldings 30 of the sections 13 and 14 are adapted for edge engagement, the said molding of one of the sections such as 13 being provided with a plurality of plates 31 with headed studs 32 thereon adapted to be received within key hole slots 33 provided in plates 34 secured to the molding 110.

30 of the opposite section such as 14. By this arrangement it will be understood that the section 13 is permanently secured to the strips 25 mounted by means of the track 5 24 and shaft 21 upon the base 11, while section 14 is removably attached to the section 13 by the connecting studs and slots 32 and 33 respectively forming the connection posts illustrated in Figs. 5, 6 and 7 of the 10 drawing.

15 A gear 35 is fixed to the shaft 21 beneath the track 24 and is in constant mesh with a suitable train of gears 36 with the power shaft 37 of the motor 12, it being understood that the said motor may be either a spring, electric or any form of motor found desirable.

20 A display case arranged in each section or half such as 14 is readily removable for arranging articles to be displayed upon the arms 27 while the manner of gaining entrance to the case will not be readily apparent when the device is assembled to any person unfamiliar with the details of construction thereof. When the motor 12 is set 25 in motion the case with its inclosed articles is caused to revolve while advertising matter may be arranged behind the upper glass panel 18 if desired and a configuration or 30 any desirable device may be arranged in the

upper chamber of the case upon the partition 16.

What I claim as new is:—

1. A device of the class described comprising two semi-cylindrical hollow sections, 35 detachable connections for the said sections concealed when the device is assembled, a partition spaced through the upper end of the device forming a top chamber therein, transparent panels for the main portion of the sections, advertisement display panels at the upper end of each section and revolving means for the sections.

2. A device of the class described comprising two semi-cylindrical hollow sections, 45 detachable connections for the said sections concealed when the device is assembled, a partition spaced through the upper end of the device forming a top chamber therein, transparent panels for the main portion of 50 the sections, advertisement display panels at the upper end of each section, a supporting base, a shaft axially arranged through the assembled sections secured to one of the same and journaled upright in the said base, 55 a gear upon said shaft and a propelling motor carried by the base operatively connected to the said gear.

In testimony whereof I affix my signature.

JOSEPH TURCEK.
